UNITED STATES PATENT OFFICE.

FRANK W. MIX, OF NEW BRITAIN, CONNECTICUT, ASSIGNOR TO THE CORBIN CABINET LOCK COMPANY, OF SAME PLACE.

TRUNK-LOCK.

SPECIFICATION forming part of Letters Patent No. 285,916, dated October 2, 1883.

Application filed May 21, 1883. (Model.)

To all whom it may concern:

Be it known that I, FRANK W. MIX, a citizen of the United States, residing at New Britain, in the county of Hartford and State of Connecticut, have invented certain new and useful Improvements in Trunk-Locks, of which the following is a specification.

My invention relates to improvements in trunk-locks of the class which are known as "hasp-locks," and the objects of my invention are to simplify the construction of the parts, to make a device which will not only lock the trunk, but which will firmly connect the trunk cover and body, and to provide a lock which, although simple in construction and inexpensive to make, will be very durable and efficient. I attain these objects by the construction illustrated in the accompanying drawings, in which—

Figure 1 is a front elevation of my improved lock, with the parts slightly separated from each other and represented as unlocked. Fig. 2 is a side elevation of the same. Fig. 3 is a rear elevation of one part of my trunk-lock, the same being represented with the parts in position for locking. Fig. 4 is a central vertical section on line $\alpha\alpha$ of Fig. 1, but with the parts represented as brought into engagement and locked. Fig. 5 is a transverse section of the lower part of my lock, the plane of section being indicated by line $y\gamma$ of Fig. 1. Fig. 6 is a front elevation of my lock, with the parts represented in the same position as in Fig. 1, but with a slight modification in the engaging parts of the hasp and the keeper. Fig. 7 is a central vertical section of the keeper and upper end of the hasp, the same being represented as engaged with each other, as shown in Fig. 6. Fig. 8 is a front elevation of another style of my improved trunk-lock, the parts being represented as unlocked and slightly separated. Fig. 9 is a plan view of the lower member of said lock, with the upper end of the hasp represented in section upon line $z\zeta$ of Fig. 8. Fig. 10 is a front elevation of another style of my improved trunk-lock, a portion of its hasp being broken away upon one side in order to show the parts behind it, the parts of this fastener being represented as unlocked. Fig. 11 is a horizontal section,

with the parts represented as brought into engagement and locked, the plane of section being indicated by the line $w\omega$ of Fig. 10.

A designates the keeper, which is adapted to be secured to the front of the trunk-cover, 55 and is provided with a dowel-pin, a , immediately above which is the projection b , for the upper end of the hasp to hook over.

c designates a raised ledge, which projects from the front of the keeper-plate A and surrounds the upper end of the hasp to protect it, and also form a better finish to the article. 60

B designates the hasp plate or frame, which is designed to be secured to the front of the trunk-body, and it has hinged to it the sprung-pressed hasp C, whose upper end is perforated or provided with an eye for engaging the upper side of the projection b upon the keeper-plate A. At the upper end of this plate B is a bridge or cross-piece, d , which has an open 70 space upon the back side to form a socket for the dowel-pin a . Said bridge d also forms the staple or keeper for the lock-bolt e .

Upon the front of the plate or frame B, I form two outwardly-projecting ribs, f , which 75 extend longitudinally with said plate for nearly its whole length, and in between which ribs the hasp C shuts closely, so that said hasp is protected from lateral vibration for nearly its whole length. This frame is provided with a 80 rectangular opening through it, as shown by the rear view, Fig. 3, and by the side of said opening, near the lower end, I form trunnion-recesses g , which are mere open recesses and are formed in the act of casting. 85

A little above the lower end of the hasp C trunnions h are formed, which fit into the recesses g g . (See Fig. 8.) The body of the hasp C is cast in box form, so as to form a case for the lock. The lock-bolt e , adapted to be 90 thrown by means of a key, (its lock mechanism being of ordinary construction,) is placed within this lock-case or hasp, and is covered by the cap-plate D upon its back side, as shown in Figs. 3 and 4. After the lock is 95 properly secured to the under side of the hasp C, the hasp is slipped endwise through the opening in the frame B, and then the trunnions h are dropped into the recesses g , and the hasp is secured in place by means of the spring k . 100

The end of this spring is curved, so that it has a constant tendency to throw the hasp outward into the position represented in Figs. 1 and 2. The lower end of the hasp, which projects 5 below the trunnions *h*, strikes against the back side of this spring when the hasp is opened, and limits the outward motion of said hasp. This spring is of sufficient strength to thus 10 act as a stop for the hasp, to hold the hasp within its bearings during transportation; but when the parts are once secured to the front of the trunk-body, the spring is supported and backed by said front, so that a light spring is sufficient for all practical purposes. The space 15 or opening in the lower part of the bridge or staple *d* is smaller than it is at the upper part, and the rear side of the dowel-pin *a*, which depends from the keeper-plate *A*, is recessed or cut away, so as to allow the lock-bolt to 20 pass upward behind a part of the dowel-pin, as shown in Fig. 4.

When the parts are secured upon a trunk in the manner hereinbefore suggested, and the trunk-cover is brought down, the dowel-pin *a* 25 enters the mouth of its socket and brings the plates *A* and *B* into proper position for engagement of the parts for locking. The dowel-pin and socket also prevent the trunk from racking, and thereby causing a strain upon the 30 working parts of the lock. After the trunk-cover has been brought down so as to bring the dowel-pin and socket into engagement, the hasp *C* is depressed against the power of its spring, so as to bring its upper end into engagement with the projection *b*, to hold the trunk down, when by the application of the proper key the lock-bolt *e* is thrown into the 35 position represented in Fig. 4, so as to hold the hasp into engagement with the projection *b* of the keeper. When in this position the hasp is protected by the flanges *ff* for nearly its whole length, so as to make a very firm fastening. The dowel-pin and socket also prevent an undue lateral strain from being brought 40 upon this hasp, while at the same time this dowel-pin does not enter the lock proper.

The lock-bolt, instead of being made to take hold of the dowel-pin, merely engages with the lower side of the bridge *d* and prevents the 45 hasp from swinging outward, so as to liberate its upper end from the projection *b*, thus making a very secure, cheap, and simple lock, so arranged as not to be liable to injury from the usual racking strain and severe usage to 50 which trunks are subjected.

The parts represented in Figs. 6 and 7 are the same as those hereinbefore described, with the exception that the keeper is provided with an eye or opening, and the projection *b'*, which 55 engages therewith, is formed upon the upper end of the hasp *C*. All of the other parts in said figures are lettered the same as in Figs. 1, 2, 3, 4, and 5.

In Figs. 8 and 9 I have represented a lock 60 in which the keeper-plate *A'* has three dowel-pins, *a'*. Said keeper-plate is also provided

with the locking projection *b'* for engagement with a recess upon the back side of the upper end of the hasp *C'*. This hasp *C'* is secured to the plate or frame *B'* and is thrown outward 65 by a spring; but instead of having the lock secured to the hasp, the hasp is in the form of a frame, and the lock *D'* is secured to the plate *B'*. This plate *B'* is also provided with three sockets at its upper end for engagement with 70 the dowel-pins *a'*, and the hasp is provided with a staple, *d'*, at a point just above the upper end of the lock *D'*. After the parts are brought into engagement, as before described, and the hasp pressed inward, so as to engage its upper 75 end with the projection *b'*, the lock-bolt *e'*, by the application of a proper key, is thrown upward and into the staple *d'*, thereby holding the hasp into engagement with the projection *b'* of the keeper *A'*, substantially in the manner of the lock herein first described.

The lock shown in Figs. 10 and 11 is changed from that shown in the other figures by what may be termed a "reversal" or "inversion" of the parts. In this lock I intend to apply the 80 keeper-plate *E* to the front of the trunk-cover. I hinge to the hasp-plate *F* the hasp *G*, which is made in loop form, and which is also pressed outward by means of a spring, as in the other figures. The lower end of this hasp I provide 85 with a loop or staple, *m*, for engagement with the lock-bolt *n*. I also provide the lower edge of the hasp-plate *F* with three dowel-pins, *o*, and the upper part of the plate *E* is provided with corresponding sockets to receive said 90 dowel-pins. The middle one of these sockets is formed in the back side of the locking projection *p*, as indicated by the broken lines in Fig. 10. Upon the front of the lower part of the plate *E*, I secure the lock *H*, which may be 95 of any ordinary construction. After closing the trunk, so as to bring the parts into proper engagement, the lower end of the hasp *G* is depressed, so as to bring its staple *m* directly in front of the lock-bolt *n*, after which the 100 lock-bolt may be thrown into the staple, as shown in Fig. 11, and thereby firmly secure the hasp in its locking position, with its loop-shaped lower end engaged with the projection *p*.

I am aware that trunk-locks have been heretofore provided with a dowel-pin and socket, when the dowel-pin entered a part of the lock and when it was secured thereto by having the lock-bolt brought into locking engagement with said dowel-pin. Such a combination of a dowel-pin and lock I hereby disclaim.

I am also aware that separately-formed dowel-pins and sockets have been placed upon a 115 trunk, in addition to a trunk-lock, and I do not claim the same.

I claim as my invention—

1. In a trunk-lock, the combination of the hasp-plate, the hasp hinged thereto, the spring 120 arranged to press upon the hasp, with a constant tendency to throw it outward, the keep-

er-plate, the dowel-pin and socket, and the lock-bolt for locking the hasp into engagement with the keeper, substantially as described.

2. In a hasp-lock, the combination of the 5 spring-pressed hasp, the plate to which it is hinged, the supports which extend lengthwise with the plate for supporting the hasp laterally thereon for nearly its whole length, and a suitable lock mechanism, said hasp and 10 its lock being both secured to the same plate, substantially as described, and for the purpose specified.

3. In a hasp-lock, the combination of the 15 hasp C, bearing a lock upon its rear side and trunnions g near its lower end, the frame or plate B, having an opening therein through which to insert the hasp C, and having trun- nion-recesses upon its rear face, and the spring k, for holding the hasp within the recess, throw- 20 ing the hasp outward, and for acting as a stop, substantially as described, and for the purpose specified.

4. In a trunk-lock, the combination of the plate A, having the dowel-pin a, the plate or frame B, having the bridge d, and the swinging 25 hasp C, bearing the lock and lock-bolt e, the parts being combined so that the dowel-pin and plate both engage the bridge d, substan- tially as described, and for the purpose speci- fied.

5. In a trunk-lock, the combination of the 30 hasp-plate, the hasp hinged to said hasp-plate, the keeper-plate, the lock-bolt for locking the hasp into engagement with the keeper, and the dowel-pin and socket at the meeting edges 35 of said two plates, all combined substantially as described, and for the purpose specified.

FRANK W. MIX.
